UNITED STATES PATENT OFFICE.

JOHN WILLIAM FREEMAN, OF SOUTH CARLTON, AUSTRALIA.

FURNACE.

Application filed October 10, 1924. Serial No. 742,910.

In the utilization of coal as a fuel in boiler furnaces the problem of attaining such a high degree of combustion that the passage to the flue of gases and the promotion of smoke will be reduced or eliminated, has occupied the attention of many minds over a long period of time and the methods adopted for the prevention of smoke have extended along widely different lines. This problem 10 has been the concern of the applicant for many years and a close study of same under practical conditions and following numerous experiments has revealed that smoke promotion arises from the fact that the extent 15 of area above the fire bars in the furnace tube and within which combustion is effected has not been taken into consideration.

In most types of furnaces in which coal is burnt the furnace tube has for the purposes 20 of strength and stability been constructed as a cylinder and the fuel carrying surface of the grate has been located below the horizontal centre line or diameter of the cylinder.

As a consequence the space above the grate 25 is considerable and permits the gases, evolved by the process of combustion of the fuel, to mix and escape unburnt from the greatest zone of heat and to pass out of the furnace tube as smoke.

30 It is well recognized that the escape and commingling of the said gases promotes smoke and it obviously follows that if same can be prevented then smokeless combustion can be attained.

35 Now according to this invention the objective of smokeless combustion in furnaces is obtained by a construction of the furnace tube whereby the area above the grate surface is materially restricted, when compared with present practice, and, in addition to such restriction the surface shape of said area is constituted so as to form, with the grate surface, an approximately flat rectangular area. The accompanying drawings 40 depict a furnace tube constructed to provide the restricted area mentioned and reference will now be made to such drawings.

Figure 1 is a vertical longitudinal section 45 of the front end of a boiler of the ordinary Lancashire type.

Figure 2 being a vertical transverse sec-

tion on line II—II in Fig. 1 through the furnace tubes.

The full line position of the upper surface 55 3^a of the furnace tube 3 is in accordance with the present invention and it will be noted that the upper surface of the fire bars coincides with the plane passing through the horizontal diameter indicated by the center 60 line e—f of the semicylinder forming the lower half of the tube so that the space above the fire bar to the top 3^a of the tube is considerably less than the space below the fire bar to the bottom 3^b of the tube. 65

Referring now to Figure 2 it will be noted that the surface of the furnace tube 3 above the fire bars 4 does not coincide with the circumferential line of a sector of a circle but that the vertical portions proceed in a 70 straight line and the upper ends of such portions merge into an arch of comparatively zero curvature.

In Figure 2 the line 5 indicates the top 75 edge of the usual furnace bridge.

As the shape of the tube furnaces 3 above the fire bars 4 is not the usual cylindrical shape it is desirable to specially support same against collapsing pressure as by means of the stays 6 from the shell 7 of the 80 boiler and also by making the furnace tube in short sections.

The staying and jointing of the short sections of the tube will be carried out in any well known manner and in accordance with 85 regulations in force regarding the manufacture and testing of boiler furnaces.

The height of the upper arch portion of the furnace tube 3 above the fire bars will be determined by the character and quality 90 of the coal being used on the fire bars and as coal produced in various parts of the world varies in quality over a wide range, it is not possible to define such height with in fixed limits. 95

It may, however, be stated that from experiments, conducted with average quality black coal used for steam production and obtained in Australia, it has been found that the height in the ordinary cylindrical tube 100 having a diameter of three feet should be lowered approximately six inches towards the horizontal centre line of such a tube.

I claim:—

In furnaces, a furnace tube of uniform cross section wherein the upper portion above the fire bar has straight vertical sides merging into a flat arch and the lower portion of the tube is semicylindrical and a fire bar in said tube so located that its upper surface coincides with the plane passing through the horizontal diameter of the semi-cylinder forming the lower half of the tube so that a restricted area is provided above 10 said bar and a correspondingly enlarged area is provided below said bar.

Dated this 7th day of August 1924.

JOHN W. FREMAN.
